UNITED STATES PATENT OFFICE.

CHARLES COMSTOCK AND OLIVER VANORMAN, OF RACINE, WIS., ASSIGNORS
TO THE RACINE WAGON AND CARRIAGE COMPANY, OF SAME PLACE.

COMBINED CORNER-IRON AND GATE-LOCK FOR WAGON-BODIES.

SPECIFICATION forming part of Letters Patent No. 249,810, dated November 8, 1881.

Application filed May 28, 1881. (No model.)

To all whom it may concern:

Be it known that we, CHAS. COMSTOCK and OLIVER VANORMAN, of Racine, in the county of Racine, and in the State of Wisconsin, have invented certain new and useful Improvements in Combined Corner-Irons and End-Gate Locks for Wagon-Bodies; and we do hereby declare that the following is a full, clear, and exact description thereof.

10 Our invention relates to combined devices for locking the end-gates of wagon-bodies, and will be fully described hereinafter.

In the drawings, Figure 1 is a cross-section of a wagon-body, giving an inside view of the 15 end-gate and rear corner-irons, the gate being locked in place. Fig. 2 is a detail, showing the end-gate unlocked; and Fig. 3 is a perspective view of the locking device detached.

A is the wagon-body, and B the end-gate, 20 carrying at each end a pivoted hook, C. D are the inner binding-pieces of corner-irons E. These corner-irons are secured in place by suitable bolts, which also secure the binding-pieces D to the side and end pieces of the wagon.

Each binding-piece D is provided with an inner 25 catch or projection, d, for the hook on the adjacent end of the end-gate to catch over, and we usually cast this projection d with the binding-piece D.

It will be seen that our device is very simple 30 and quite as effective as any in the market for the purpose, and does away with any locking-projections on the outside of the body.

Having thus described our invention, what we claim as our invention is—

35 The binding-pieces D of the corner-irons, having catches or projections d, in combination with hooks C, adapted to be pivoted to the end-gate of a wagon-body, as set forth.

In testimony that we claim the foregoing we 40 have hereunto set our hands this 10th day of May, 1881.

CHAS. COMSTOCK.
OLIVER VANORMAN.
